GAME

August E. Opalka, Mount Clemens, Mich.

Application September 5, 1934, Serial No. 742,814

1 Claim. (Cl. 273—46)

The object of this invention is to provide a simple and inexpensive game apparatus adapted for playing a game having some of the characteristics of bowling and some of the characteristics of billiards. The invention is illustrated in the accompanying drawing and consists in certain novel features which will be first fully described and then more particularly defined in the appended claim.

10 In the drawing:

Figure 1 is a plan view of a game apparatus embodying the present invention.

Figure 2 is a side elevation of the same.

Figure 3 is an enlarged longitudinal section, 15 more particularly showing the pin-setter.

Figures 4 and 5 are elevations of playing implements.

In carrying out the invention, there is provided a supporting frame 1 of any suitable construction 20 on which is secured a table 2 of oblong form having a rail 3 extending along its two sides and across one end. Secured upon the table longitudinally thereof is an elongated block 4 which has one end flush with the front end of the table and its rear 25 end spaced from the rear transverse rail, as clearly shown in Figure 1, the space 5 between the rear end of the block and the rear rail receiving the playing ball and fallen pins after each shot, and the spaces 6 at the sides of the block constituting runways for the return of the ball to the player. The top of the block 4 is smooth and level and constitutes an alley over which a pool or billiard ball 7 is to be propelled by striking it with a cue 8 in a well-understood manner. At the rear end of 30 the alley, pins 9 are set up as targets to be struck by the ball, and these pins are preferably shaped to simulate tenpins and are set up in the triangular formation customary for the pins in bowling.

As shown clearly in Figure 3, the pins 9 have 35 sockets 10 in their lower ends which are to engage over spotting pins 11 when being arranged for a shot. The spotting pins are secured upon a triangular carrying plate 12 and rise vertically therefrom through guide openings provided therefor in the table and the alley, as shown in Figure 3. The spotting pins and the guide openings are arranged in triangular relation and the pins, in 40 their raised position, will project somewhat above the surface of the alley to be engaged by the tenpins so that the latter will be accurately set up. To the side edges of the plate 12 are pivoted the

lower ends of links 13 which are pivoted at their upper ends to the lower forwardly bent ends of levers 14, said levers being fulcrumed upon the side rails of the table and connected at their upper ends by a handle bar 15. The weight of the pins 11 and the carrier plate 12 overbalances the levers and handle bar so that normally the pins are retracted and will not interfere with the falling movement of a tenpin which is struck by the ball 7 or by another falling pin. Pressing upon the 10 handle bar will rock the levers to raise the spotting pins and hold them raised until the pressure is released when they will automatically descend.

16 designates stops at the front ends of the runways 6 to prevent the returned ball rolling off the 15 table.

From the foregoing description, taken in connection with the accompanying drawing, it will be seen that I have provided means for playing a game resembling both billiards and bowling and in 20 which a high degree of skill may be acquired. The ball is placed at or near the front end of the table and then struck by the cue so as to be propelled toward the tenpins, and scores are counted according to the established rules of bowling. 25

Having described my invention, what I claim is:

A game apparatus comprising a table including supporting means, a top secured to said supporting means and extending therefrom to provide a relatively long overhanging end portion, an elongated block extending longitudinally of the top and spaced from the sides thereof to provide runways and from the end of the overhanging portion, said block providing an alley and having vertical guide openings therethrough that extend through 30 the overhanging portion, spotting pins movable through the guide openings, a triangular plate carrying the spotting pins and disposed below the overhanging portion, links pivotally secured to the sides of the triangular plate, oppositely disposed levers fulcrumed to the sides of the overhanging portion and having curved lower ends pivotally connected to the links, a handle bar bridging the upper ends of the levers and secured thereto for raising the plate against the action of 45 gravity for elevating the pins through the guide openings, tenpins to be set up on the alley and having sockets therein to receive the spotting pins, a ball and means for propelling the ball over the alley toward the tenpins. 50
